BAR-BARREL CHAIR

Irving R. Kaufman, Los Angeles, Calif.

Application April 25, 1950, Serial No. 9,468

Term of patent 14 years

(Cl. D15—1)

To all whom it may concern:

Be it known that I, Irving R. Kaufman, a citizen of the United States, residing in the city and county of Los Angeles, and State of California, have invented a new, original, and ornamental Design for a Bar-Barrel Chair, of which the following is a specification, reference being had to the accompanying drawing, forming part thereof.

Fig. 1 is a front perspective view of a bar-barrel chair, showing my new design with the bar closed.

Fig. 2 is a rear perspective view thereof with the bar open.

I claim:

The ornamental design for a bar-barrel chair, substantially as shown.

IRVING R. KAUFMAN.
